[57] CLAIM

The ornamental design for a combined comb and nail file, as shown and described.

DESCRIPTION

FIG. 1 is a perspective view of a combined comb and nail file showing my new design;

FIG. 2 is a top plan view thereof;

FIG. 3 is a front elevational view thereof, the rear being a mirror image thereto;

FIG. 4 is a bottom plan view thereof;

FIG. 5 is a left end elevational view thereof; and

FIG. 6 is a right end elevational view thereof.
